U.S. Appl. No. 10/674,797, filed Jun. 9, 2020, Sunne et al.

Primary Examiner — Llorellys Martinez*(74) Attorney, Agent, or Firm* — Dentons US LLP(57) **CLAIM**

The ornamental design for an earring, as shown and described.

DESCRIPTION

FIG. 1 is a perspective view of a first embodiment of an earring;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof;

FIG. 8 is a perspective view of a second embodiment of the earring;

FIG. 9 is a front view thereof;

FIG. 10 is a rear view thereof;

FIG. 11 is a right view thereof;

FIG. 12 is a left view thereof;

FIG. 13 is a top view thereof; and,

FIG. 14 is a bottom view thereof.

Broken lines shown in drawings illustrate portions of the earring that form no part of claimed design.
